FOLDED TRANSMISSION LINE

Nils E. Lindenblad, Rocky Point, N. Y., assignor
to Radio Corporation of America, a corporation
of Delaware

Original application September 24, 1942, Serial
No. 459,497. Divided and this application No-
vember 21, 1945, Serial No. 630,075

6 Claims. (Cl. 178—44)

1

This application is a division of my previous application Number 459,497, filed September 24, 1942.

The present invention relates to electrical circuits having characteristics similar to those of transmission lines.

An object of the present invention is the provision of an artificial line having uniformly distributed characteristics.

Another object of the present invention is the provision of an artificial line which is compact in size.

Still another object of the present invention is the provision of an artificial line having a low characteristic impedance.

Still another object of the present invention is the provision of an artificial line having characteristics which do not vary with changes in the frequency of energy applied thereto.

A further object of the present invention is the provision of an artificial line which has a phase shift characteristic which is linear with respect to frequency.

Still a further object of the present invention is the provision of a compact artificial line which, in spite of its size, will handle large amounts of energy.

The foregoing objects, and others which may appear from the following detailed description, are attained in accordance with the principles of the present invention by so folding a natural line that it occupies a small space without at the same time introducing such mutual inductive effects, either electrostatic or electromagnetic, between different layers of the folded line that it ceases to act as a natural line.

The present invention will be more fully understood by reference to the following detailed description, which is accompanied by a drawing in which Figure 1 illustrates an embodiment of the invention, while Figure 2 illustrates an exploded view of a part of Figure 1, while Figure 3 illustrates a modification of the invention.

The embodiment of the present invention, shown in Figure 1, employs a plurality of generally H-shaped metal plates 47 having a conductor strip or ribbon 42 laced in a zig-zag manner between the plates. The conductor strip is covered with insulating material 43 which may be in the form of flat strips of cloth or the like on either side of the ribbon 42. Alternatively the ribbon may be covered with an insulating sleeve woven over the ribbon. The plates 47 are maintained in close pressed relationship against the conductive ribbon 42 by means of

2

bolts 25 passing through suitable apertures in the plates 47.

Figure 2 illustrates an exploded view of a portion of Figure 1, illustrating more clearly the manner in which the conductor 42 is folded back and forth in a zig-zag manner between the conductive ground plates 47. Each end of conductive ribbon 42 is provided with terminal bolts 46 for connection to the desired utilization apparatus.

A modification of the present invention, shown in Figure 3, includes a plurality of the artificial line units as described above connected together and placed in a metallic casing 34. The casing 34 may be filled with transformer oil 52 whereby the insulation between successive elements of the conductor may be improved. Furthermore, the presence of the insulating oil enhances the cooling of the artificial line and thus permits the use of higher power. The conductive casing 34 is closed with an insulating top 35 bearing a terminal 36 which is connected to one end of ribbon 42 of one of the sections within the casing. The other end of the ribbon may be grounded to the casing by means of ground strip 50.

While I have particularly shown and described several modifications of the present invention, it should be clearly understood that the invention is not limited to these forms alone, but that modifications may be made.

What is claimed is:

1. An artificial line including a plurality of spaced metallic plates having an elongated conductor folded in zig-zag manner between said plates and insulating means between said plates and said conductor, and means for clamping said plates firmly against the successive folds of said conductor.

2. An artificial line wherein a number of assemblies as set forth in claim 1 are connected in series and immersed in an insulating fluid.

3. An artificial line wherein a number of assemblies as set forth in claim 1 are connected in series and immersed in insulating fluid, said plates being connected together to a point of zero reference potential.

4. An artificial line including an elongated conductor having insulating sleeve woven about said conductor, said conductor being folded back and forth in a zig-zag manner so as to occupy a restricted space and conductive shield plates between the successive folds of said conductor to reduce the mutual effects between said elements.

5. An artificial line wherein a number of assemblies of lines as set forth in claim 1 are con-

nected in series and immersed in an insulating liquid.

6. An artificial line wherein a number of assemblies of lines as set forth in claim 1 are connected in series and immersed in insulating liquid, said plates being connected together to a point of zero reference potential.

5 NILS E. LINDBERG.
